LOCKING CLOSURE FOR FLEXIBLE
TANK OUTLETSLou S. Janczak, South Bend, Ind., assignor to
United States Rubber Company, New York,
N. Y., a corporation of New Jersey

Application October 30, 1948, Serial No. 57,449

4 Claims. (Cl. 222—507)

1

This invention relates to a closure for a flexible outlet, and particularly to the means for clamping the closure thereon and to a means for forming a pouring spout when the closure is removed.

The closure embodying this invention is particularly suitable for use on collapsible tanks for liquids, the walls of which being made of rubber coated fabric and have a filling and draining opening therein, to the margin of which is secured an outwardly projecting flexible rubber outlet. Such tanks are designed to withstand the relatively great impact pressure of the liquid therein when they are dropped from a height of 20 feet.

Among the objects of this invention is to provide a closure cap for the flexible outlet which will maintain a fluid type seal for the outlet under the high pressures developed on it by the liquid within the tank.

A further object of this invention is to provide a closure for the outlet which may be quickly applied and removed manually and without the use of tools.

A still further object of this invention is to provide a convenient pouring outlet, or spout for the relatively short tank outlet after the closure therefor has been removed.

This invention and its foregoing objects and other advantages are further described in connection with the accompanying drawings, in which:

Fig. 1 is a plan view of a collapsible tank having a closure embodying this invention placed on its outlet opening, but not clamped thereto;

Fig. 2 is an elevation of the collapsible tank shown in Fig. 1, and having parts broken away to show the self contained pouring spout, which is adapted to be attached to the tank outlet when the closure is removed;

Fig. 3 is an enlarged vertical cross-sectional view of the closure on the tank outlet, taken on line 3—3 of Fig. 1; and

Fig. 4 is an enlarged plan view of a half section of the closure showing parts taken in section on line 4—4 of Fig. 3.

Referring to Figs. 1 and 2 of the drawings, this invention comprising a closure 10 and the pouring spout 11 in combination therewith is applied to a flexible outlet 12 of a collapsible container 13, which may be made of flexible rubber coated fabric material, and adapted to hold a body of liquid 14, within which the pouring spout 11 is suspended by a flexible connection 15 from the closure 10, when it is positioned on the outlet 12. The closure 10 is preferably made of a light metal, such as aluminum.

As shown in all of the figures of the drawings, the closure 10 is placed on the outlet 12, but is not clamped thereto. Referring to the enlarged Fig. 3, the tank outlet 12 comprises a flexible de-

2

formable vulcanized unit of rubber having a flange 16 which is bonded to the flexible walls 17 of the tank. The outlet 12 is provided with a flexible tubular lip 18, which extends outwardly of the tank 13 from the base of the outlet. The lip 18 is adapted to be sealed by a rigid plug 19, which extends into the interior of the lip 18. The plug 19 is preferably made of metal, and is pivotally connected to an outer metal cap 20 by a rivet 21 extending through a central opening in the top plate 22 of the plug and the top of the cap 20. A washer 23 surrounds the body of the rivet, and is placed between the top plate 22 of the plug 19 and the top of the cap 20 for the purpose of spacing these members from each other. The interior and exterior flanges 24 are beaded over the margins of the openings in the cap 20 and the plate 22 to pivotally connect the parts together, and permit the cap 20 to be rotated in respect to the plug 19.

The closure plug 19 is provided with an annular groove 25, into which an annular bead 26 on the outlet lip 18 is adapted to fit, after the plug has been forced into the lip and the supporting flange 27 on the plug rests on top of the lip. The closure 10 is adapted to be secured to the outlet 12 by clamping the outlet lip 18 against the sides of the plug by means of a radially contractible clamping band 28, which encircles the lip 18 and is supported by the top of the plug 19. As shown in Fig. 4, the clamping band 28 has overlapping ends 29 and 30, which are adapted to slide over one another to permit the band to contract. The clamping band 28 is affixed to the plug top 22 near one end 30 of the band by a bracket 31, which may be riveted, or otherwise secured to the band and to the top plate 22 of the cap. As shown herein the bracket 31 is attached to the plate 22 by rivets 32. The clamping band 28 may be slidably supported on the top plate 22 of the plug 19 at other points by means of one or more angle brackets 33, which slidably rest upon the plug plate 22, and may be secured to the band 28 with rivets 34.

45 A toggle linkage 34 is provided for contracting the clamping band 28 against the lip 18 of the outlet 12. The toggle linkage 34 comprises two links 35 and 36 which are pivotally connected together at or near one of their ends by a pin 37. The other end of the link 35 is pivotally connected to the end 29 of the clamping band 28 by a pin 38 and the other end of the link 36 is pivotally connected to the band 28 near its end 30 by a pin 39, which extends through the link 36 and the attaching bracket 31 of the band 28.

40 A portion of the vertical side, or rim, of the outer cap 20 is cut away to provide an opening 40, through which the toggle links 35 and 36 are adapted to project. The toggle links are in full lines as they appear in their unclamped position,

and when they are moved to their clamped position, they occupy the position as shown by the dot and dash lines. Such movement of the toggle linkage is produced by the rotation of the cap 20 in respect to the closure plug 18. When the plug is inserted in the interior of the lip 18, it is held with sufficient friction to permit the cap 20 to be manually rotated in respect thereto about the pivoting rivet 21. Upon the rotation of the cap 20, the linkage 34 is operated by cam surfaces 41 and 42 formed at each end of the opening 40 in the side wall of the cap. When the cap is rotated in the direction of the arrow A, the cam surface 41 rides over the curved link 35 and forces it inwardly towards the center of the cap and thereby collapses the linkage and contracts the clamping band by causing the slidably ends 29 and 30 to ride over each other. When the linkage 34 has been moved to its dot and dash line position, the clamping band 28 has been sufficiently contracted to tightly force the sealing bead 26 of the lip 18 into the groove 25 of the closure plug 18, and thereby tightly clamp the closure to the outlet 12. The link 35 is provided with an extension 43, which is curved outwardly, and is adapted to lap over the cam surface 42 on the cap 20, when the toggle linkage is in its clamped position. In order to unclamp the band 28, the cap 20 is rotated in the opposite direction to the arrow A, and in so doing, the cam 42 operates upon the link extension 43, and rides along the toggle link 35 to force the linkage to its unclamped position as shown by the full lines in Figs. 1 and 4.

After the closure 18 has been released from the lip 18, it may be removed from the outlet for the purpose of either filling or emptying the tank 13. In the event the tank is to be filled, the closure is merely placed to one side, and it will be held connected to the tank by the flexible connection 15, which is attached to the closure plug, as particularly shown in Fig. 3, by tying a knot 44 in the end of the cord 15 after it has been extended through an eye bracket 45 on the plug 18. The other end of the cord 15 is attached to the pouring spout 11 by extending the lower end of the cord through an opening in the outer end of the spout, and tying a knot 46 in that end of the cord 15. When it is desired to pour fluid from the tank 13, the cord 15 is used to draw the upper end of the pouring spout 11 through the lip 18 of the tank outlet. The operator may then grasp the projecting end of the spout 11 and pull the lower end into the base of the outlet. The pouring spout 11 is preferably made of a vulcanized rubber composition and is provided with a groove 47 positioned between a bead 48 and a flange 49. The groove 47 is adapted to receive an annular bead 50 on the base of the tank outlet 12, and thereby form a fluid tight seal between the spout 11 and the outlet 12. After the spout 11 has been pulled into its final position, the fluid 14 in the tank 13 may be poured therefrom into the opening of a consumer tank without spilling the fluid.

Whereas the preferred form of this invention

has been shown and described herein, it will be understood that changes in the details thereof may be made without departing from the spirit of the invention or the scope of the appended claims.

Having thus described my invention, what I claim and desire to protect by Letters Patent is:

1. A closure for a flexible outlet comprising a closure plug adapted to be inserted within said outlet, a cap pivoted on said plug and having a downwardly extending rim which encircles said outlet, a band clamp positioned between said rim and said outlet, said cap rim being rotatable in respect to said band clamp, and means on said clamp and operated by said rim for clamping the wall of said outlet between said plug and said clamp.

2. A closure for a flexible outlet comprising a closure plug adapted to be inserted within said outlet, a cap pivoted on said plug and having a downwardly extending rim encircling said outlet, a split band encircling said outlet between said rim and said outlet and supported by said plug, and a toggle mechanism affixed to the separated ends of said band and operated by said rim for clamping said outlet between said band and said plug.

3. A closure for a flexible outlet comprising a closure plug adapted to be inserted within said outlet, a cap pivoted on said plug and having a downwardly extending rim encircling said outlet, a split band encircling said outlet between said rim and said outlet and supported by said plug, a toggle mechanism operated by said downwardly extending rim and affixed to the separated ends of said band for clamping said outlet between said band and said plug.

4. A closure for a flexible outlet comprising a closure plug adapted to be inserted in said outlet, a rotatable cap pivotally mounted on said plug and having a rim adapted to encircle said outlet, a ring positioned within said rim and encircling said flexible outlet, said rim being rotatable in respect to said ring, and means operated by the rotation of said rim in respect to said ring for clamping said outlet between said ring and said plug.

LOU S. JANCZAK.
